CENTRIFUGAL SWITCH MECHANISM

Victor Weber, St. Louis, Mo., assignor to The Emerson Electric Mfg. Co., St. Louis, Mo., a corporation of Missouri

Application June 6, 1935, Serial No. 25,268

16 Claims. (Cl. 200—80)

This invention relates to electric switches and is particularly adapted to centrifugally operated switches. As disclosed, the device may be applied to a rotor having means movable in response to the speed thereof, which movable means actuates the switch. It, therefore, lends itself to the control of the starting circuit of a motor, that may be cut out as soon as the motor reaches predetermined speed.

10 It is an object of this invention to provide such a device that is simple in operation, easy to make, inexpensive, and having a minimum number of parts.

15 It is another object of this device to provide such a switch providing continuous and substantially constant contact pressure throughout the time the switch is closed.

20 It is a further object of this invention to provide a plurality of levers and a spring for determining the position of these levers, and for using the same spring to establish the breaking of contact.

25 It is a further object to provide a switch of this kind which, in its operation, has a wiping action of the contact elements.

30 It is another object to provide a switch of this kind having no change in direction of forces upon the moving parts during the acts of making and breaking contacts, wherefore, the switch is not noisy.

35 It is an additional object of this invention to avoid the necessity of employing flexible wire connections between moving and stationary parts, this being avoided by designing the device so that the pivot pressure between the movable and fixed members is a multiple of contact point pressure and does not vary appreciably during the operation.

40 Further advantages will appear in the description herebelow.

In the drawings:

Fig. 1 is an edge elevation partly in section of the switch applied to a rotor, the rotor being stationary.

45 Fig. 2 is a view similar to Fig. 1, but with the rotor moving and hence the centrifugal elements extended.

Fig. 3 is a section on the line 3—3 of Fig. 1.

Fig. 4 is a section on the line 4—4 of Fig. 1.

50 Fig. 5 is a section on the line 5—5 of Fig. 2.

Fig. 6 is a vertical section through the switch proper, the actuating mechanism being removed.

Fig. 7 is a view of the back plate of the switch mechanism.

55 This switch is adapted to be employed, for ex-

ample, on a machine here shown as comprising a stator 10 and a rotor 11, the rotor being mounted on and rotating with a shaft 12. The end housing of the machine is designated at 13 and it has therein a journal 14 supporting the shaft 12. Studs 15 are on the end plate 13 and they are adapted to receive and support the switch proper, such as is shown in Fig. 6. The switch proper may include a securing plate 16 to assist in fastening the device to the housing. 10

Over this is mounted a base 17 made of non-conducting material, shown in detail in Fig. 7. Extending through this base 17 is a U-shaped contact element 18 to which is secured one side of a circuit as at 19. The U-shaped plate has ears 15 20 projecting through suitable openings 21, as shown in Fig. 7, to the rotor side of the base 17. A second U-shaped contact member 24 is secured also to the base 17 and out of contact with the member 18. The other side of the circuit, as at 20 25, is fastened in conducting relation to the plate 24. The member 24 has ears 26 extending through suitable openings 27 to the rotor side of the base member 17. Pivoted in the ears 26 is a lever 28, the pivot being adapted to conduct electricity from the ears 20 into said lever 28. At one end the lever is provided with a contact pole 29. It is likewise provided with a bent over portion 30 that maintains the pole 29 at all times spaced at least a given distance from the base 17. 30

Pivoted in the ears 26 is a longer lever 31, the pivots for which are provided by turned up arms 32 engaging in ears 26. At one end of the lever 31 and in cooperative relationship with the contact 29 of the lever 28, is a contact 33. Between the two levers and also located between the pivots thereof is a spring 34 insulated from one of the levers as by insulation 35, here shown as being on lever 31. Depressions 36, formed, for instance, by stamping, in the two levers are designed to maintain the insulation and the spring in proper position. It will be observed that the lever 28 is a lever of the first class, whereas lever 31 with respect to the spring action is a lever of the third class. The lever 31 at its end opposite the contacts is bifurcated, having two arms 37 that straddle the rotor shaft 12. From Fig. 7 it will also be apparent that the base plate 7 likewise straddles this shaft. These arms 37 are bent at their outer ends, as shown at 38 in Fig. 6, for the purpose to be shown hereafter. It may be noted, however, that the switch actuating pressure is applied to the portions 38 whence the lever 31 pivots about its pivots 32, moving the contact 33 against the spring to touch the contact 29. The 55

spring urges both levers in the same direction of rotation. Hence the positive movement of lever 31 against the action of the spring 34 is effected by force directed against portions 38. Then, when 5 the contact 33 touches contact 29, any further movement of the lever 31 will force the lever 28 counterclockwise also against the spring 34. It will be seen, therefore, that the spring 34 urges both levers out of contact when no force is applied at 38, but when such force is applied, causing movement of the lever 31, the spring urges the lever 28 into intimate contact with the lever 31, at their respective contacts 29 and 33.

It is further to be observed that the compression of the spring 34 by movement of the levers is relatively small compared to the initial compression thereof. By this means, a substantially constant force acting on the contacts is effected.

The actuating mechanism for this switch includes a fixed element 40 secured to the rotor 11 of the motor. This fixed member 40 has upstanding end plates 41. The member is also adapted to receive the shaft 12 and be placed thereover. Centrifugally weighted bell cranks 42 are pivoted as at 43 to the end plates 41 of the member 40. These bell cranks carry cross rods 44 on their inner ends. A sleeve 45 fits slidably over the shaft 12, and is provided with a cut out upstanding portion 46 in which the cross bars 44 engage. A spring 47 acts between the fixed member 40 and the upstanding portion 46 and tends to force the sleeve member 45 outwardly from the rotor 11. Of course, it will be understood that the centrifugal weights in swinging out force the sleeve toward the rotor against the spring 47.

The operation of the device is as follows:

When the rotor is not moving, as shown in Fig. 1, the centrifugal weights 42 are held inwardly parallel to the shaft by means of the spring 47 that forces the sleeve member 45, and consequently rods 44, outwardly. The upstanding portion 46 of the sleeve 45 then engages the upstanding bent portion 38 of the lever 31, pivoting this lever about its pivots 32 so that the contact 45 33 engages the contact 29 and lifts the lever 28 against the action of the spring 34. It will be seen that the spring 34 therefore has the double function of urging the contact 28 into close contact with the contact 33 when the lever 31 is raised, and also, as will be shown hereafter, of tending to separate the two levers. In this position, the circuit from 18 to 25 is closed through ears 28, levers 28 and contact 29 to contact 33, lever 31, and ears 28. This may close the starting circuit for the motor. As the motor comes up to speed, the weights 42 swing outwardly and, by means of the rods 44, force the sleeve 45 toward the rotor and away from the lever 31. This permits the spring 34 to press the lever 31 downwardly, followed by the lever 28, and as soon as the lug 30 engages the base 17, the lever 28 is stopped. During this action of course there will be a substantially constant and continuous force acting to urge the contacts together, until the lever 28 is halted. The contacts 29 and 33 are in face to face engagement at the point of halting of the lever 28, and further movement of the lever 31 to remove the contact 33 from the contact 29 causes a sudden withdrawal of the said contact while the entire surfaces of contact are practically parallel. In other words, at the break no portion of either of the contacts remains closer to the other to sustain an arc that would cause unequal wear. By this operation, the starting circuit of a motor or the like may be cut out

upon the motor's reaching a predetermined speed.

In closing the switch, the contact 33 first comes into contact with the pole 28 without moving the lever 28. As the outward movement of the contact 33 continues, this contact is caused to wipe across the contact 28 by virtue of the greater radius of curvature of the lever 31 than that of the lever 28. This wiping action insures a good electrical contact between the two switch poles. And during the entire operation there is always a force acting in the same direction to urge both of the levers into contact with their respective ears by means of their pivots. This insures good conduction of the electricity into or out of the levers, and eliminates the necessity of providing separate flexible conductors for each lever.

Wherefore it will be understood that a device has been provided that is simple in construction and operation, with a minimum number of parts and which accomplishes all of the desired objectives previously listed.

What is claimed follows:

1. In a switch mechanism of the kind described, a base, a pair of levers independently pivoted thereto, said levers overlapping, a spring means for urging one lever toward contact with the other, and the other away from contact with the first.

2. In a switch mechanism of the kind described, a base, a pair of levers pivoted thereto, a contact on each lever, said contacts being adapted to be brought into registry, and said pivots of said respective levers being at different distances from said contacts, whereupon when said levers are moved with said contacts contiguous to each other, one contact will wipe across the other.

3. In a switch mechanism of the kind described, a base, a pair of levers pivoted thereto and both movable thereon, a contact on each lever, said contacts being adapted to be brought into registry, said contact arms of said levers being of different lengths, whereby when said levers are pivoted said contacts are brushed one across the other, and said contacts having flat faces adapted to register coplanarly at the instant preceding the complete separation of the contacts.

4. In a device of the kind described, a base plate, a first lever pivoted thereto at a point between the ends thereof, a second lever pivoted in like manner, said levers having contiguous end portions, resilient means engaging between said levers, and acting on one of them outside of its pivot and the other inside of its pivot with respect to said contiguous end portions whereby said resilient means urge both levers in the same pivotal direction.

5. In a switch mechanism, a base plate, means pivoting a pair of levers thereto, said levers and said pivot means comprising conductors, said levers being movable with respect to the base, and means urging said levers into contact with their pivoting means constantly during the movement of the levers, whereby uninterrupted currents of electricity may flow through said pivot means into said levers.

6. In a switch mechanism, a base plate of non-conducting material, two pairs of pivot elements extending upwardly from said base member, and constituting two pivot devices, a lever pivoted in each pivot device, means for urging said levers into close contact with their respective pivot devices continuously during oscillation of said levers, whereby electric current may be passed into

said levers through said pivots, said means also urging both said levers toward predetermined positions about their respective pivots.

7. In a device of the kind described, a base member, a lever pivoted intermediate its ends to said member, a second lever pivoted to said member and extending for a distance alongside said first lever, and said levers having registerable end portions, said first lever extending at its opposite end beyond said second lever, whereby pressure upon such free end causes the other end to contact said shorter lever, and means for urging said shorter lever into contact with said longer lever at their contiguous ends.

15 8. In a device of the kind described, a base member, a first lever pivoted thereto, a second lever independently and fixedly pivoted to said member alongside said first lever, means urging both levers to pivot in the same direction, and means limiting the movement of one lever whereby, upon moving said first lever against said urging means, it may be brought into contact with said second lever, said levers being then adapted to move together, and said urging means 20 urging said second lever against said first lever.

30 9. In a device of the kind described, a base member, a first lever pivoted thereto, a second lever pivoted to the base member independently of said first lever and lying alongside said first lever and adapted to contact therewith, an electrical contact on each lever at said point of contact, means urging said levers toward said base member at their contiguous ends, and stop means 35 on one lever arresting its movement toward the base, whereby the other lever may move out of contact therewith and separate said electrical contacts.

40 10. In a device of the kind described, a base member, a pair of levers independently pivoted thereto, one lever overlying the other lever, and adapted to contact therewith, said levers being pivoted at different distances from their contiguous end portions whereby, when pivoted together, one will wipe across the other, and spring 45 means acting between said levers and between said respective pivots whereby to urge said levers in the same direction.

50 11. In a device of the kind described, a base member, a pair of levers pivoted thereto, one lever lying alongside the other lever for at least a portion of the length of the latter, and said levers being adapted to contact with each other adjacent one end of one of them, the pivot means for said levers being spaced at different distances 55 from said contact point, spring means acting between said levers at a point between said two pivot means, and tending to urge both levers to pivot in the same direction, and stop means on one lever arresting its movement and permitting the other lever to move away therefrom.

60 12. In a switch mechanism, a base plate, a pair of U-shaped members mounted on said base plate in spaced relation to provide two pairs of upstanding ears, two levers, one pivoted in each pair of ears, said levers lying alongside each other for at least a portion of the length of one of them, and adapted to contact adjacent the end of one of them, and means for (1) urging said

levers apart, (2) urging one of said levers toward the other, and (3) urging both of said levers into intimate contact with their respective ears to provide good conductivity between said ears and said levers.

5 13. In a mechanism of the kind described, a pair of members one of which is differentially movable relative to the other, a switch mechanism on one member, and an actuating device on the other, said switch member including a base, a pair of levers pivoted thereto and adapted to contact each other at one point, said levers being pivoted at different distances from said point of contact, means urging both of said levers to pivot in one direction, said actuating device 15 including an element adapted in response to the operation of said member positively to move one end of one of said levers toward the contiguous end of the other, against said urging means, and said urging means then acting to force said other 20 lever into contact with said one lever.

25 14. In an electric machine having a movable member and a fixed member, a switch mounted on said fixed member, actuating mechanism for said switch mounted on said movable member, said switch including a base, two levers pivoted thereto and adapted to contact with each other, means acting between said levers and urging both of them to pivot in one direction, one of said levers extending adjacent said actuating means, 30 said actuating means having an element movable in response to the speed condition of said movable member against said lever to urge it to pivot against said urging means and into contact with said other lever, said urging means then acting 35 to force the other lever strongly against said one lever, and said actuating means operating in response to other speed conditions of said movable member to move away from said lever, whereby said urging means may move said levers and they 40 may become out of contact with each other.

45 15. In an electrical switch mechanism, a base member, a first lever pivoted intermediate its ends to said base member, a contact point on one end of said lever, a second lever pivoted to said base intermediate its ends and having a contact point on one end, said second lever overlying said first lever whereby the contact points on both may be brought together, the pivot of said second lever being between the contact point and pivot point 50 of the first lever whereby the free end of the second lever extends between said contact point and said pivot point of said first lever, and means engaging said first lever between said two points and said free end of said second lever, to urge 55 said second lever toward said first lever and said first lever away from said second lever.

60 16. In an electrical switch mechanism, a base, a pair of levers pivoted thereto, said levers overlapping and adapted to contact each other adjacent the end of one of them, an electrical contact on each lever at said point of contact, means for urging the first lever into contact with the second, and for urging the second away from the first, and a stop on said first lever whereby, after 65 contact has been established, further movement of the second lever will break it away from said contact.

VICTOR WEBER.
